UNITED STATES PATENT OFFICE.

EDMUND OCUMPAUGH, 2d, OF ROCHESTER, NEW YORK, ASSIGNOR TO DEFIANCE MACHINE COMPANY, OF ROCHESTER, NEW YORK, A CORPORATION OF NEW YORK.

PRINTING-MACHINE.

1,154,050.

Specification of Letters Patent. Patented Sept. 21, 1915.

Application filed January 23, 1914. Serial No. 813,874.

To all whom it may concern:

Be it known that I, EDMUND OCUMPAUGH, 2d, a citizen of the United States, and resident of Rochester, in the county of Monroe 5 and State of New York, have invented certain new and useful Improvements in Printing-Machines, of which the following is a specification.

This invention relates to printing-machines of the type in which any of a series 10 of characters or words may be impressed selectively upon a check or other article. The invention, while having features applicable to various machines of this type, is particularly applicable to machines of the kind 15 commonly designated as "check-writing machines", in which characters are provided for filling in the amounts of bank-checks.

One object of the invention is to improve 20 the manually-operable mechanism by which both the selective and the impressing operations of the printing-means are controlled, particularly to produce an arrangement in which two easily performed movements of a 25 pair of manually-operable members serve for the accomplishment of both of these inventions.

To the foregoing end the invention comprises the use of mechanism in which two 30 manually-operable members, adapted to be grasped simultaneously by one hand, are arranged to have a rocking movement for the selective operation, and to be compressed together to produce the impressing opera- 35 tion.

Another object of the invention is to improve the means by which the check, or other article to be printed, is held in position between the printing instrumentalities, 40 and to this end I employ an arrangement in which two rollers or other instrumentalities engage and hold the work at opposite sides of the printing-means, and in which a single yoke-shaped member supports both of 45 said instrumentalities, so that they may be raised simultaneously to permit the introduction or removal of the work.

In the accompanying drawings:—Figure 1 is the front-elevation of a machine embodying the present invention; Fig. 2 is a 50 vertical section, on the line 2—2 in Fig. 1, but on a larger scale; Fig. 3 is a vertical section on the line 3—3 in Fig. 2; and Fig.

4 is a side-elevation, partly in vertical section, to show in detail certain features of the 55 work-holding mechanism.

In the illustrated embodiment of the invention the printing instrumentalities comprise a type-wheel 5 and a platen 6. The type-wheel carries a series of types arranged to form words expressive of various numbers, and it is journaled in horizontal position so that the characters may be brought selectively into working position by rotation of the wheel. The platen 6 and the 60 types are preferably serrated so as to have a cutting action on the paper of a check.

The manually-operable means for controlling the action of the printing-means comprise two members 7 and 8, which are so positioned that they may be grasped simultaneously by one hand of the user. The member 7 is an arm projecting integrally from a sleeve 9 which is journaled horizontally in the casing 10 of the machine. Also 70 integral with the sleeve 9 is a segmental plate 11, having gear-teeth on its periphery which mesh with a pinion 12 fixed to the type-wheel. Accordingly, the type-wheel may be rotated by swinging the arm 7 forwardly or rearwardly, thus producing the selective operation of the printing-means. To indicate the position in which the type-wheel stands a pointer 13 is fixed to the plate 11, and it works through a slot in the casing, and cooperates with a graduated scale 85 14, as shown in Fig. 1. To further assist the selective operation, the plate 11 is provided with a series of depressions 16, which are engaged by a spring-pressed detent 15. This 90 detent does not prevent movement of the plate, but it tends to cause the plate to come to rest in the several positions corresponding to the selective positions of the type-wheel, in which one or another of the lines of type 95 is directly above the platen 6.

The second manually-operable member 8 is in the form of a lever pivoted at 17 on the arm 7. The inner end of this lever engages a plunger 18, which slides loosely 100 through the center of the sleeve 9 and engages, in turn, a bell-crank lever 19, which is journaled on a fixed pivot in the casing and enters the sleeve 9 through a lateral opening therein, as shown in Fig. 3. The 105 lever 19, in turn, is pivoted to a rod 20, of

which the lower end engages an adjusting-screw 21 threaded in a lever 22 which carries the platen 6. This lever is mounted on pivots 23, so as to swing about an axis substantially at the level of the work-table 25. A spring 24, attached to the rear end of the lever 22, tends to maintain the platen in its depressed position, with the lever 8 swung away from the arm 7; but after the selective 10 operation of the mechanism, the impressing operation is produced by pressing the lever 8 toward the arm 7, thus, through the connections just described, causing the platen to rise and press the work against the type-wheel.

Two ink-rollers 26 are journaled in position to engage the type-wheel in the usual manner.

In order that the work may be held firmly 20 in position upon the work-table 25 during the impressing operation, I employ means comprising two rollers 27 and 28, which are journaled in opposite sides of a yoke-shaped member 29. This member is mounted on 25 pivots 30 at its ends, so that it bridges the forwardly-projecting part of the casing in which the type-wheel is mounted, and two springs 31, engaging the yoke at its ends, tend to swing it downwardly so as to force 30 the rollers into engagement with the work. Coöoperating with the rollers 27 and 28 are two rollers 32 and 33, which are located beneath the work-table. The roller 32 is journaled in fixed position, and it and the 35 roller 27 are preferably provided with co-operating slots and flanges to hold the work more securely against lateral movement. The roller 33 is a feed-roller, being serrated, as shown in Fig. 2, to increase its hold upon 40 the work. This roller is actuated, by any ordinary or suitable mechanism, to feed the work intermittently after each impressing operation.

It will be apparent that the machine just 45 described is capable of convenient and rapid operation in the printing of checks, or the performance of similar work. The selective operation is easily performed by the rocking movement of the members 7 and 8, and 50 is then immediately followed by the impressing movement without removing the hand from these members, and owing to the use of the hand-grip for this latter purpose a considerable pressure may be transmitted

to the platen without inconvenient effort on the part of the user.

My invention is not limited to the embodiment thereof hereinbefore described and illustrated in the accompanying drawings, but it may be embodied in various other forms within the nature of the invention as it is defined in the following claims.

I claim:—

1. In a printing-machine, the combination, with printing-means adapted to impress any of a series of characters selectively, of mechanism, for actuating the printing-means, comprising two manually-operable members adapted to be gripped simultaneously by the hand and movable laterally, to cause a selective operation, and toward each other, to cause an impressing operation. 65

2. In a printing-machine, the combination, with printing-means adapted to impress any of a series of characters selectively, of mechanism for actuating the printing-means, comprising a rocking member, two grip-members carried thereby and movable toward and from each other, and connections, between said parts and the printing-means, 75 through which the rocking movement of said rocking member is translated into a selective operation of the printing-means, while the relative movement of the grip-members is translated into an impressing operation 80 of the printing-means.

3. In a printing-machine, the combination, with printing-means adapted to impress any of a series of characters selectively, and comprising a type-wheel and a platen, of a 90 casing inclosing the printing-means, a rock-shaft mounted horizontally in the casing and projecting at one side thereof, a gear-segment carried by said shaft, a pinion meshing with the gear-segment and connected with the type-wheel, an arm projecting upwardly from the rock-shaft, a lever pivotally mounted on the rock-shaft so as to move toward and from said arm, a plunger within the rock-shaft coöoperating with 95 said lever, and mechanism connecting said plunger with the platen, whereby the platen may be moved toward the type-wheel when the lever is pressed toward the arm. 100
